UNITED STATES PATENT OFFICE.

PHILIPPE F. MABILLE, OF CAMBRIDGE, MASSACHUSETTS.

DESIGN FOR AN ORGAN-CASE.

SPECIFICATION forming part of Design No. 23,508, dated July 24, 1894.

Application filed March 22, 1894. Serial No. 504,737. Term of patent 7 years.

To all whom it may concern:

Be it known that I, PHILIPPE F. MABILLE, a citizen of the United States, residing at Cambridge, in the county of Middlesex and State of Massachusetts, have invented and produced a new and original Design for Organ-Cases, of which the following is a specification, reference being had to the accompanying drawing, showing the same.

This design for organ cases is shown in the accompanying drawing in which the figure represents in perspective an organ case.

The feature of this design is as follows: From the back of the case in the upper portion project forward two curved bracket arms G, a horizontal bar F extending from each one toward the other, with a horizontal board E between the two which form one line from one bracket to the other. From the board E depends two arms D, an elliptical frame C being between the two in which frame is a looking glass A. On the lower ends of the depending arms D are knobs or balls H, and

on each side of each arm is a bracket J, which extends up to and is connected to the under side of the board E, these brackets being grooved on their front faces in radial lines, extending toward the junction of the arms with the board, being somewhat of fan shape, the lower edges of the bracket being in curved lines substantially concentric or in line with the elliptical frame.

On each side of the case on the end pieces L under the curved brackets J are horizontal circular lamp shelves M each having a partial border of vertical spindles N connected together at their upper ends by a portion of ring or rim P.

Having thus described my improved design for organ-cases, what I claim is—

The design for an organ case herein shown and described.

PHILIPPE F. MABILLE.
